UNITED STATES PATENT OFFICE.

ELMER O. BEARDSLEY, OF CHICAGO, AND WALTER F. PIPER, OF OAK PARK, ILLINOIS,
ASSIGNORS TO THE BEARDSLEY & PIPER COMPANY, OF CHICAGO, ILLINOIS, A
CORPORATION OF ILLINOIS.

METHOD OF FILLING MOLDS FOR FOUNDRY.

1,427,349.

Specification of Letters Patent. Patented Aug. 29, 1922.

Application filed July 21, 1921. Serial No. 486,546.

To all whom it may concern:

Be it known that we, ELMER O. BEARDSLEY, and WALTER F. PIPER, both citizens of the United States, and residents of Chicago, in the county of Cook and State of Illinois, and Oak Park, in the county of Cook and State of Illinois, respectively, have invented certain new and useful Improvements in Methods of Filling Molds for Foundry, of which the following is a full, clear, and exact description.

The invention relates to the filling of molds used in metal founding by projection of the sand. In the practice of the invention set forth in Letters Patent No. 1,309,835, dated July 15, 1919, difficulty has been experienced in properly projecting and packing sand in some portions of flasks and which are formed with decidedly inwardly 20 and upwardly convergent walls or with undercut spaces, particularly when the flask is provided with a constricted inlet opening, because the sand projected at a non-variant angle would leave unfilled spaces or loose sand in the pockets under the convergent sides or which are otherwise inaccessible.

The primary object of the invention is to provide an improved method by which sand projected at a non-variant angle will be projected to properly pack and fill undercut spaces or pockets in the flask.

Another object of the invention is to provide an improved method in filling molds by which excessive spattering of the sand in the flask and the tendency of the sand to displace the flask will be lessened.

The invention consists in the several novel features hereinafter set forth and more particularly defined by claims at the conclusion 40 hereof.

In the drawings: Fig. 1 is a side elevation of apparatus embodying the invention. Fig. 1 is a detail of the projector. Fig. 2 is a vertical section, taken on line 2-2 of Fig. 3, of the apparatus for carrying and manipulating the flasks. Fig. 3 is a front elevation, parts being shown in section.

An apparatus for practicing the improved method is exemplified in a portable carriage 50 which permits the flasks to be readily delivered to and removed from the projector and comprises axles 4 sustained by carrying-wheels 5 and side-frames 6 rigidly secured to the axles and provided with standards 7.

A flask-carrier is pivotally sustained by a 55 rod 8 which is carried by the upper ends of standards 7 and comprises a top wall 9 which is formed to function as a pattern-plate for pipe-patterns 10, pendant side-walls 11 and end-walls 12. A flask 13, having upwardly convergent side-walls 14, between which is formed a constricted longitudinally extending opening 14^a to receive the molding sand, end-walls 15 and an open bottom, is adapted to rest on the pattern-plate of the tiltable carrier and hold the sand around the patterns to form one section of a mold for founding. Studs 22 on the carrier are adapted to pass through holes in lugs 23 on the flask to relatively position 70 the pattern-plate and flasks and hold them against relative lateral movement.

This apparatus is particularly adapted to support the pattern-carrier and flask under a sand-projector of the type set forth in 75 our Letters Patent No. 1,309,833, dated July 15, 1919, in which the projector is movable horizontally in any direction to fill all portions of a mold by projection of the sand downwardly in a non-variant direction. 80 This machine comprises a projector comprising a casing 16, a rapidly revolving rotor 18^a with projector-blade 18^b to project wads of sand downwardly at high speed. A motor 17 for driving the rotor; an arm 18 85 which is pivoted at 19 and by which the motor and projector are supported in operative relation; a jib 20 to the outer end of which arm 18 is pivoted and which is pivoted on a standard 21, and suitable means 90 for feeding sand in regulated quantity to the projector for rapid projection. For a more detailed description of such a machine, reference may be had to our said patent.

In filling a flask with a constricted inlet 95 or undercut portions or pockets not directly accessible from the top, as exemplified by the flask for making pipe-molds illustrated in the drawings, the sand would not properly fill those portions of the mold which lie 100 under the outer portions of the sides 14 and more particularly those portions adjacent the outer sides of the patterns 10. To make it possible to fill flasks of this character, the flask-carrier is pivotally supported by rod 8, 105 so the flask may be tilted to either side to bring the inlet opening of the flask and the undercut portions of its walls into position

- so the line of delivery of the sand will be downward in the proper direction to pack the sand into such portions, as shown by the dotted arrow in Fig. 2.
- 5 Mechanism is provided for securing the flask and carrier in different positions and for this purpose a segmental rack 24 is fixed to one of the standards 7 and a toothed block 25 carried by a lever 26 is movable 10 into and out of mesh with the rack by the lever. The latter is pivoted to the carrier at 27 and is provided with a handle 28 positioned adjacent a handle 29 fixed to the carrier. Lever 26 is normally held in position 15 to hold the block locked to rack 24 by a spring 30 which has one of its ends connected to the inner end of the lever, as at 31, and its other end connected to the carrier, as at 32. In order to cushion the flask 20 and carrier in their different positions, springs 33 and 34 are interposed between the ends of the locking-block 25 and abutments on lever 26, the block being slideable on the lever for that purpose.
- 25 In operation, the flask is placed on the carrier, and the carriage is then moved into range of the projector of the moulding machine. The operator will then release the carrier and tilt it so the flask will be positioned to permit the downwardly projected wads of sand from the projector to pass through the inlet opening of the flask and directly to either of the spaces between the outer sides of the patterns and the flask-sides, and will then set the locking-lever 30 so that the carrier and flask will be retained in said position. The projector will then be operated to project sand into and to pack it in that portion of the flask which is then 35 in the direct line and path of projection to form the corresponding portion of the mold. Then the carrier and flask will be tilted and set into oppositely inclined position, so as to bring the space between the outer side of the other pattern and the other flask-side 40 in the line and path of projection intersecting the inlet opening. The projector will be over the flask until this space has been filled and packed with sand. Next, 45 the carrier and flask will be set into horizontal position and the projector will be operated to fill all of the unfilled space between and over the patterns and until the flask has been completely filled and uniformly packed with sand the sand being projected adjacent the arrow shown by full lines in Fig. 2. During each step of this 50 operation, the projector will be shifted longitudinally of the flask to fill one portion thereof from end to end. The filled flask 60 will then be lifted off the carrier and placed with a mating flask to form a complete mold. In all positions, the carrier and flask 65 will be cushioned by springs 33 and 34 and, as a result, there will be no excessive spattering of the sand by the impact of the sand against the surfaces and sand in the flask which results in high speed projection. This cushioning is also advantageous in lessening the tendency of the projected sand 70 to displace the apparatus when it is mounted on a portable carriage.
- The invention exemplifies a method of filling flasks by high speed projection, in which provision is made for projecting sand 75 directly into undercut spaces or those which are inaccessible by sand projected in a constant direction; also a method in which the spattering effect of the wads of sand under high speed projection and the tendency of 80 such sand to vibrate or displace the flask are lessened by cushioning the flask.
- The invention is not to be understood as restricted to the precise practice set forth, since it may be modified within the scope 85 of the appended claims, without departing from the spirit and scope of the invention.
- Having thus described the invention, what we claim as new and desire to secure by Letters Patent, is:
1. That improvement in making molds which consists in projecting sand in a constant direction, and tilting a flask into different positions relatively to the line of projection and projecting the sand directly 90 into undercut and otherwise inaccessible spaces in the flask.
2. That improvement in making molds which consists in projecting sand in a constant direction, tilting and holding the flask 100 in different positions relatively to the line of projection, and moving the projector over the flask in its different positions so that the sand will be projected directly and packed in undercut and otherwise inaccessible 105 spaces.
3. That improvement in making molds which consists in projecting sand into a flask and cushioning the flask.
4. That improvement in making molds 110 which consists in projecting sand into a flask, shifting the flask to vary the line of delivery of the sand, and cushioning the flask.

ELMER O. BEARDSLEY,
WALTER F. PIPER.
